UNITED STATES PATENT OFFICE.

BERRY MACK O'BRIEN, OF SANGERVILLE, MAINE.

DENTAL MIRROR.

Application filed March 25, 1925. Serial No. 18,234.

My invention relates to improvements in mirrors of the type adapted to be inserted in the mouth of a patient and used in conjunction with any source of light to reveal the condition of teeth or other parts within the mouth which could not otherwise be conveniently or thoroughly inspected.

An object of the invention is the provision of a mirror of the character described which is adapted to be manipulated more quickly and easily after having been placed in the mouth of the patient to disclose a relatively great number of parts within the mouth than is possible with a dental mirror of ordinary construction.

A further object of the invention is the provision of a dental mirror having reflecting surfaces provided on the opposite faces thereof and which is adapted when placed within the mouth of the patient to hold the cheek away from the gums while at the same time being capable of use to perform the functions of an ordinary dental mirror.

Other objects and advantages of the invention will be apparent from the following description, considered in conjunction with the accompanying drawings, in which—

Figure 1 is a perspective view of the improved dental mirror, in one position for use,

Figure 2 is a transverse section through the mirror.

The improved mirror comprises a substantially flat body 1 which is shown as being substantially circular in outline and as having a pair of plates 2 and 3 respectively of substantially the same diameter. The plates 2 and 3 are disposed flatwise upon each other with the centers thereof in line so that annular rim flanges 4 and 5 on the plates 2 and 3 respectively are disposed at opposite sides of the body 1. The plates 2 and 3 are secured together in the position just described in any suitable known manner, as by means of solder. Obviously, the plates 2 and 3 may be integral with each other and formed as a single member, if desired. The body 1 is provided at each of the opposite sides just mentioned with a reflector which may be a circular glass plate 6 that fits in the rim flange 4 of the plate 2 and the circular glass 7 that fits in the rim flange 5 against the plate 3, the glass plates 6 and 7 being retained in the rim flanges 4 and 5 respectively in any suitable known manner, as by bending the edge portions of the rim flanges in-

ward after the glass plates are in place in the rim flanges. The glass plates 6 and 7 of course are provided with a backing of quick silver or the like, as shown.

A handle 8 for supporting and manipulating the body 1 is shown as being a rod-like member having an attaching portion 9 secured in a socket or recess 10 in the periphery of the body 1, said socket being shown as comprising cooperative shallow radial grooves in adjacent faces of the plates 4 and 5. The attaching portion 9 extends at an obtuse angle to the remainder of the handle 8. The outer end portion of the handle 8 is shown as being reduced at 11 and as provided with screw threads 12, whereby the handle 8 may be attached to any suitable dental instrument or supplementary handle, not shown, with which it can be used advantageously.

From the foregoing description of the various parts of the device, the operation thereof may be readily understood. Since the body 1 has reflecting surfaces at opposite sides thereof, it is manifest that the inspection of a greater number of parts within the mouth can be effected by means of the device than is possible with ordinary single faced dental mirrors. Moreover, the device can be used in the mouth of a patient to throw or reflect light upon the teeth when the device also is being employed to hold the cheek away from the gums of the patient.

Obviously, my invention is susceptible of embodiment in forms other than that illustrated in the accompanying drawings, and I therefore consider as my own all such modifications and adaptations of the form of the device exhibited therein as fairly fall within the scope of the appended claim.

I claim:—

A mirror of the character described comprising a body formed of a pair of plates of circular outline secured flatwise together with the centers of the plates aligned, said plates having axially extending rim flanges, mirrors fitting in said rim flanges, said plates having registering radial grooves in their adjacent faces cooperating with each other to provide a radial socket in said body, and a handle comprising an attaching portion secured in said socket, the remaining portion of the handle being rod-like and extending at an obtuse angle to said attaching portion and to the plane of said body.

BERRY MACK O'BRIEN.
